UNITED STATES PATENT OFFICE

103,909

DESIGN FOR AN ENSEMBLE DRESS

Tora Coleman, New York, N. Y.

Application February 20, 1937, Serial No. 67,762

Term of patent 3½ years

To all whom it may concern:

Be it known that I, Tora Coleman, a citizen of Latvia and a resident of the Borough of Manhattan, city of New York, county of New York, and State of New York, have invented a new, original and ornamental Design for an Ensemble Dress, of which the following is a specification, reference being had to the accompanying drawing, forming part thereof, wherein

Figure 1 represents the front and

Figure 2 represents the rear of an ensemble dress showing my new design.

The dress ensemble comprises a dress section (having a blouse and skirt) and a jacket. The

two figures of the drawing show the jacket in place. The sleeves are part of the blouse of the dress section, the jacket being sleeveless. The chevron-like element at the front is a part of the blouse, only that portion of the chevron being seen which appears at the front opening of the jacket.

The back of the blouse is conventional in appearance.

I claim:

The ornamental design for an ensemble dress, as shown and described.

TORA COLEMAN.
